HEATING SYSTEM

Karl F. Hartmann, San Francisco, Calif., assignor of one-half to Morgan J. Doyle, San Francisco, Calif.

Application January 14, 1938, Serial No. 185,020

2 Claims. (Cl. 237—2)

This invention relates to heating systems such as are employed in apartment houses, office buildings, large houses and the like where unit radiators distribute heat in the various rooms or apartments and it is desired to control the flow of heat vehicle to any particular unit in accordance with the need therefor.

It is the principal object of this invention to provide an improved heating system of this character and this and various other related objects will be apparent to those skilled in the art upon reference to the following specification and accompanying drawings in which,

Fig. 1 represents diagrammatically and fragmentarily a building provided with a heating system according to my invention;

Fig. 2 is an elevational section through one end of the valve control and operating unit of the system.

In the embodiment of the invention herein illustrated, a building 2, having a plurality of segregated spaces 4, such as apartments or rooms, to be heated, and a service space 6, such as a basement or the like, is served by various utilities such as a gas main 8 providing a source of fluid under continuous and substantially uniform pressure, and a water main not shown.

Spaces 4 are individually provided with radiators 10 through which a heat vehicle such as water may move due to thermal or mechanical pumping action in a manner well known in the art from and to a heater 12, via risers 14 and returns 16 respectively. Means are provided for supplying fuel to the heater which may consist of a gas burner 18 connected to the gas main 8.

In order to prevent the flow of heat into a space 4, either when the space is not in use or the temperature is above that needed, a valve 20 is placed between each radiator unit and the heating vehicle riser 14. In buildings where quiet should prevail it is necessary not only that the valve 20 seat positively against flow therethrough, but also that the valve closing operation occur at a low speed so that very little kinetic energy be available to produce a vibration throughout the system upon seating of the valve. This slow movement to closed position is accomplished in the embodiment shown in the drawings by means of a valve motor driven by the available illuminating gas under pressure.

The gas is conveyed to the various valves by means of conduits 22, and that gas which is expended in the operation of the valves is vented by ducts 23 to a safe point such as at 24 in the heater fire box.

The valve, valve motor, and motive pressure control thereof is more clearly illustrated in Fig. 2 in which there is shown the valve body 26 interposed in line 27 connecting the radiator and the riser 14. A movable valve element 29 is adapted to close the port 30 in said valve body and is reciprocable by a fluid pressure responsive motor, comprising, as here shown, a diaphragm 32 sealed between two chamber forming members 34 and 36, to divide the resulting chamber into 10 complementary pressure chambers 38 and 40, and secured to said valve element 29 by a plunger 42, passing through suitable glands 44 and 46, as illustrated.

Means are provided for controlling the admission of gas from line 22 to actuate the diaphragm in either direction and as here illustrated the same takes the form of a slide valve 41 having gas line 22 connected to a chamber 5 thereof at port 50. A set of ports 52 and 54 are, respectively, 20 connected with the pressure chambers 38 and 40. A set of ports 56 and 58 provide vent ports which are connected to the safety vent 23. Reciprocably and nonrotatably mounted in chamber 5, is a plunger 60 held in position to connect main 22 with chamber 38 and to effect release of gas from chamber 40 through ports 54 and 58 via duct 62, by a spring 64. In the position shown gas pressure acts to positively hold the water valve 28 closed. As will be observed, the water valve 28 is normally held closed by the gas main pressure. In order to open the valve 29, plunger 60 is forced against the action of spring 64, to permit communication between chamber 38 and vent 23 via ports 52 and 56 and to connect main 22 directly 35 to chamber 40. Gas entering chamber 40 slowly but positively forces diaphragm 32 upwardly and opens valve 29.

Means are provided to actuate plunger 60 comprising an electromagnet 66 having an armature 68 disposed to engage connector rod 70 disposed through closure nut and gland 72 on valve 48. The electromagnet 66 is energized from any suitable source of current under control of a switch 74 which may be of the manual or thermostatic variety. Quite evidently, energization of the electromagnet actuates valve 48 to a position to admit gas beneath the diaphragm and open valve 29 so as to permit the hot water in riser 14 to enter the radiator.

If the switch 74 is of the thermostatic type set to open at desired room temperature, such as 68° F., the opening thereof permits spring 64 to actuate plunger 60 to water valve closing position as heretofore explained.

- While gas pressure, as of ordinary illuminating gas mains, is the medium described as furnishing the energy to actuate diaphragm 32, it is recognized that water from the water mains may be used as well and vented to any suitable drain. Of course, since water main unit pressures are many times in excess of domestic gas pressures, the size of motor may be decreased accordingly. However it is desirable that the ports 52 and 54 be of such a small size with reference to the volume of chambers 38 and 40, that the rate of movement of the valve 29 is slow enough to prevent any appreciable impact.
- Having described my invention, I claim:
1. In a device for use in a building having a fluid heating system comprising unit radiators, a source of continuously uniform fluid fuel pres-

sure and a fuel burner connected to said fuel source positioned to heat the fluid in the heating system; valves associated with each radiator unit for controlling the flow of fluid of said heating system to said unit radiators, means driven by fluid from said fuel pressure source for operating the valves from open to closed position and vice versa, means for discharging the fluid expended on said driven means, and means for controlling the flow of the fluid to said driven means and for controlling the discharge of fluid from said driven means.

2. In a device as in claim 1, means for conducting the fluid discharged from said driven means to said fuel burner for burning. 15

KARL F. HARTMANN.
